UNITED STATES PATENT OFFICE.

SAMUEL H. POLASKY, OF CHICAGO, ILLINOIS, ASSIGNOR TO F. A. HARDY & COMPANY, OF CHICAGO, ILLINOIS, A CORPORATION OF ILLINOIS.

SHIELD FOR WELDERS AND THE LIKE.

1,313,908.

Specification of Letters Patent. Patented Aug. 26, 1919.

Application filed February 24, 1919. Serial No. 279,021.

To all whom it may concern:

Be it known that I, SAMUEL H. POLASKY, a citizen of the United States, and a resident of the city of Chicago, in the county of Cook and State of Illinois, have invented 5 certain new and useful Improvements in Shields for Welders and the like, of which the following is a specification.

My invention has reference to means for 10 protecting the eyes and faces of workmen, especially persons employed in welding or cutting with electric arc apparatus and similar pursuits, in which the protection of the eyes is desirable.

15 Heretofore, so far as I am aware, protection afforded the workmen engaged in such employments has been in the shape of goggles for the eyes, the lenses whereof are of extremely dark shade and nearly opaque, 20 or their faces are covered with masks provided with eye-socket openings into which are fitted suitable lenses. Many workmen object to these protectors because, owing to the density of the lenses, they are unable to 25 observe anything excepting objects immediately in the zone of the extremely bright light of the welding tool, and accidents frequently occur, due to the inability of the workman to see to one side or the other of 30 his work and bench. In addition, the masks are objectionable because they may not be worn with any degree of comfort and cannot be satisfactorily ventilated, with the result that the skin perspires too freely.

35 It is to overcome these inherent objections that I have designed the structure herein disclosed, which has for its object to provide a shield for the face of the workman and at the same time protect his eyes from 40 the intensely bright or incandescent light generated by the welding tool or similar apparatus, which the workman may be using. At the same time it is an object of my invention to avoid the use of a goggle 45 by providing a protector that will not obstruct the vision of the workman, but will permit him to observe whatever is transpiring about him, so that he may move from place to place without having to remove the 50 shield or protector. Other objects will be obvious to persons skilled in this art after an understanding of my invention is had, among which is the provision of a shield or protector for the eyes and face of a work- 55 man, that is simple in construction and

therefore easy to operate; which is efficient in performing the functions for which it is designed; and which may be economically manufactured so that it may be retailed at 60 a moderate price.

All of these objects I prefer to accomplish in a manner substantially as hereinafter described and more particularly pointed out in the claims, reference being now made to the accompanying drawings that form a part of 65 this specification, in which,—

Figure 1 is a perspective view of my improved shield showing the relative position of the parts when in use.

Fig. 2 is a vertical side elevation of the 70 same, enlarged.

Fig. 3 is a front view of the shield detached from its supporting members.

Fig. 4 is a vertical section thereof on line 75 4—4 of Fig. 3.

In the drawings I have employed the same reference characters to designate similar elements throughout the divers views, and by referring to Fig. 1 it will be observed 80 the structure preferably comprises suitable hanger element supported upon and secured to the shoulders and body of the wearer, and a frame and shield adjustably mounted with respect thereto.

The hanger element consists of parallel 85 upright and left hand straps 5 and 6, the upper portions 7 whereof are hook-shaped to extend over, fit about and rest upon the shoulders of the wearer, as shown, and means in the form of a chain α is provided 90 to fasten the hanger element securely to the workman. The chain α is secured at one end to the strap 6, whence it is passed around his back to the strap 5, where one of the links is adapted to be engaged by the 95 hook 8 thereon and in order to prevent the spreading of the straps 5 and 6, the chain is then passed taut across the workman's chest to a hook 9 on strap 6, where an adjacent link in the chain is engaged. In order to space the lower ends of the straps 5 and 6, I prefer to connect their lower portions by a horizontally disposed transverse rod 10, that also acts as the pivotal connection between the hanger element and the 105 shield supporting members.

Pivotedly mounted at their lower ends upon the rod 10, are upwardly extending parallel right and left arms 11 and 12, that are each provided with a longitudinally dis- 110

posed slot 13. Wing-nuts 14 are screwed onto the threaded opposite ends of the connecting rod 10 for the purpose of adjustably locking the straps 5 and 6 and the arms 5 11 and 12 together, and in order to insure their stability and prevent accidental movement, I prefer to make the engaging portions of these elements disk-shaped and provide the engaging faces thereof with radial serrations or corrugations 15, that interfit with each other.

10 The shield is carried in a suitable frame, consisting of right and left side-pieces 16 and 17, the lower ends whereof are connected by a tie-rod 18, the ends of which extend through said side-pieces and through the slots 13 in the arms 11 and 12. Another tie-rod 19, of slightly larger gage, connects the side-pieces 16 and 17 a slight distance 15 above rod 18, and likewise passes through said side-pieces and through the slots 13, where its ends are threaded and provided with wing-nuts 20. The ends of these rods 20 18 and 19 engaging the slots, permit of a longitudinal movement of the side-pieces 25 parallel to the arms 11 and 12, and when moved to their desired position, the wing-nuts 20 are tightened and the structure is secured together.

30 The elements thus far described are preferably of metal of a relatively thin gage for lightness, and a substantially U-shaped holder 21, of channel metal, is secured to the facing portions of the side-pieces 16 and 17, and upon the upper portion of the rod 19 by spot-welding, soldering, or in any other suitable manner. The shield 22 preferably is fitted into the channel of this U-shaped holder and is secured therein by 35 rivets or otherwise. This shield consists of a piece of fiber-board or the like, preferably light in weight, and which has good heat-insulating and fire-resisting qualities and is cut rectangular in shape and provided at 40 about its center with a fenestrum or opening 23. Secured along the vertical sides and bottom of this fenestrum, upon the side facing the wearer, are Z-shaped strips 24, so arranged, as seen in Fig. 4, that one of their 45 flanges is spaced away from the body of the shield 22 a distance sufficient to accommodate therein a relatively thick plate of transparent glass 25, or other suitable medium, for permitting a view to be obtained and 50 protecting the eyes. An angle metal strip 26 is pivotally and hingedly secured at one end to the adjacent portion of one of the upright Z-shaped strips and its opposite end is provided with a latch 27 to lock it to the 55 adjacent portion of the opposite vertical Z-strip. This angle strip 26 extends along the upper edge of the plate 25 and prevents the same being accidentally removed, while 60 suitable leaf-springs 28 are secured to the 65 inner surface of the Z-strips and bear

against the adjacent surfaces of the plate 25 to prevent relative movement of the latter. Correspondingly disposed Z-shaped strips 29 are secured upon the opposite face of the shield 22, that coat with a hinged and 70 latchable angle strip 30 to retain one or more plates 31 upon the opposite side of the fenestrum 23. These latter plates 31 may be of the dark amber or brown type, of glass such as is usually employed for protecting the eyes of welders against the glare produced by the operation, and leaf springs 32 retain them against relative movement, and by the use of one or more of such glass plates, a greater or less density may be obtained.

75 It will be understood that when the shield is in use, the hooks 7 are positioned upon the shoulders of the workman, so that the strips 5 and 6 will extend down and rest 80 upon the front portion of his body, as seen in Fig. 1 of the drawings, so that the chain 8 may be passed under the arms, around his back and engaged with the hook 9, while the remaining portion of said chain is passed 85 across his chest and engaged with the hook 9, so that the supporting or hanger element will be securely attached to the operator. The workman may then release the wing-nuts 14 and adjust the shield carrying arms 90 11 and 12 to the desired angle. The wing-nuts 20 are then released and the shield 22 and its carrying frame 16-17 is adjusted longitudinally on the arms 11 and 12, until the fenestrum has been positioned properly 95 with relation to the workman's eyes and the work on which he is engaged, and for convenience in making this adjustment, I have provided a suitable rod 33 that extends horizontally across the upper portion of the 100 shield 22 and has its ends bent laterally and secured to the adjacent portions of said shield, substantially as shown, to form a handle for moving the shield longitudinally. It will be observed that, through the angular adjustment of the arms 11 and 12, and the longitudinal adjustment of the shield 22, 105 the fenestrum may be brought into a suitable position to comfortably view the work therethrough, no matter whether the work 110 is on the eye-line of the operator or above or below the same.

115 While I have herein illustrated and described a specific embodiment of my invention, it is to be understood that I am not restricted to the precise structure disclosed as that is merely typical for the purpose of describing my invention, and I desire it understood that changes and refinements of the structure disclosed may be made, without departing from the scope of my invention as expressed in the appended claims.

120 What I claim is:—

125 1. A protector comprising an opaque shield provided with a fenestrum, angle- 130

shaped members surrounding a portion of said fenestrum and providing grooves between the same and said shield, a viewing element mounted in said grooves, a suitable frame in which said shield is mounted, parallel arms extending along the sides of said frame, means permitting the longitudinal adjustment of said frame on said arms hook-shaped shoulder engaging straps, and means connecting said straps to said arms where-
5 by the latter may be adjusted to alter the angularity between the same and said straps.

2. A viewing device comprising a fenestrated opaque plate, a suitable viewing element closing said fenestrum, parallel arms between which said plate is mounted and is longitudinally adjustable, supporting members pivoted to the ends of said arms, and means for adjusting said members and said 10 arms radially with respect to each other.

3. A viewing device comprising a fenestrated opaque plate, a suitable viewing element closing said fenestrum, parallel arms upon and between which said plate is longitudinally adjustable, supporting members the ends whereof are pivotally connected to the ends of said arms, and means for locking 15 said members and arms in divers adjusted positions.

30 4. A viewing shield comprising a fenestrated opaque plate, a suitable viewing element closing said fenestrum, longitudinally slotted parallel arms, lateral projections on said plate extended through the slots in said 20 arms, means for clamping said plate to said arms in desired positions, shoulder engag- 25 arms in desired positions, shoulder engag- 30 ing straps, means for securing said straps in

position upon the wearer, and a pivoted clamping connection between said straps and said arms. 40

5. A viewing shield comprising a fenestrated plate, a suitable viewing element closing said fenestrum, a frame having facing channels in which opposite edges of said plate are disposed, longitudinally slotted 45 parallel arms, lateral projections on said frame extended through the slots in said arms, means for clamping said frame to said arms, in adjusted positions, shoulder en- 50 gaging straps, a flexible device connected to said straps for securing the device in position upon the wearer, and a pivoted clamp- 55 ing connection between said straps and said arms.

6. A viewing shield comprising a fenestrated opaque plate, a viewing element cov- 60 ering the fenestrum in said plate, parallel bars between which the sides of said opaque plates are adjustably secured, parallel shoul- 65 der straps, a flexible element adapted to sur- 70 round the body of the wearer and having de- 75 tachable connection with the forward por- 80 tions of said shoulder straps, and a pivoted 85 clamping connection between the lower ends of said parallel bars and said parallel shoul- 90 der straps.

Signed at Chicago, county of Cook and State of Illinois, this 13th day of February, 1919.

SAMUEL H. POLASKY.
